UNITED STATES PATENT OFFICE.

JOHN IVAN FRITZ, OF GEAUGA LAKE, OHIO.

CENTRIFUGAL SEPARATOR.

Application filed June 30, 1926. Serial No. 119,671.

My invention relates to improvements in centrifugal separators and has for its object the provision of separator construction, especially adapted for handling fluids of relatively high specific gravity, containing finely subdivided or partially dissolved solid matter, such as paints, varnishes and the like. This contemplates suitable mechanism for effecting the separation centrifugally of the heavier materials suspended in the fluid body as well as such materials as are of less specific gravity than the fluid itself.

Accordingly, I have provided improved means in the centrifugal separator embodying my invention, whereby the fluid contents of the separator bowl is directed in such manner as to contribute materially to the separation, deposit and retention of the heavier solid particles, in association with suitable straining or filtering means for effecting the removal of the lighter particles.

The features of my invention may best be explained in connection with the accompanying drawings illustrating a preferred embodiment of my improvements, wherein:

Figure 1 is a view in side elevation, also partially broken away and in section, to show the features of my invention more clearly,

Figure 2 is a transverse section on line 2—2, Fig. 1, and Figure 3 is an enlarged fragmentary sectional view of the filter construction.

In each of the figures of these drawings I have employed the same character of reference to indicate identical parts.

The features of the centrifugal separator are sufficiently shown in the view in elevation to enable one to understand the construction and operation of the instant improvements, although certain details of general construction are omitted from this showing.

The bowl *a* is mounted for high-speed rotation upon the shaft *b*, stepped in the bottom of the casing *c* and driven by the gear *d* and coacting threaded portion *b'* provided upon the shaft. Above said bowl there is provided a supply pipe *e'* feeding into the receptacle *e* and having a control valve *e''* governing the flow of liquid from said receptacle into the bowl.

There is provided a central passage *a'* within the bowl, through which the treated fluid is adapted to flow into the lower portion of the bowl and beneath the diaphragm

f having perforations *f'* in two concentric rows and depending vanes *f''* disposed in quartered arrangement beneath said diaphragm, approximating in shape the bottom configuration of said bowl.

Above said diaphragm there are provided a series of frusto-conical members *g*, *g'*, *g''*, which are adjacent to the inner row of discharge openings *f'* in the diaphragm, the purpose of which will later be explained.

It will be noted that the cover *a³* of the bowl is spaced away from the tubular portion *g³* of the central separator member to form an outlet from the bowl. Positioned thereon is the filter device, comprising, as better shown in Fig. 3, a fine wire screen *h*, which may be reinforced, if desired, by a silk inner covering *h'*, or one of filter paper, for filtering out even finer particles than would be retained by the wire gauze.

Clamping members *i*, having wing nuts *i'*, are provided for securing the construction removably in assembled relation, as shown in Fig. 1, and the usual overflow and discharge spouts *j*, *j'*, are laterally positioned and connected with the respective separator compartments for withdrawing the fluid therefrom at different levels.

I may now explain the operation of my improved construction as employed in the separation of suspended pigment materials, for example, from mixed paint. The paint is discharged from pipe *e'* into the receptacle *e*, and valve *e''* is adjusted to permit the regulated flow of the mixed paint in the central passage *a'* and beneath diaphragm *f*. The vanes *f''* assist in imparting high centrifugal motion to the paint within the bowl, and the continued flow of such paint causes it to rise through the perforations in the diaphragm with the heavier portions thereof initially following the course of the darts as indicated in Fig. 1 of the drawings.

Assuming that the centrifugal bowl is filled with the pigment-charged paint, some of the heavier ingredients will be trapped below the diaphragm *f* and lodge circumferentially thereof intermediately of the vanes, tending constantly to free the openings *f'*. As the surcharged paint rises beneath the frusto-conical members *g*, *g'*, *g''*, these tend to deflect the heavier ingredients outwardly where they collect somewhat in successive strata under the influence of centrifugal force, thereby constantly clearing the paint from its heavier and coarser ingredients.

which constantly seek the outer walls of the rotating bowl. This action is materially contributed to by the axially positioned members, having abrupt under faces and gradually inclined upper faces to cause the flow of the partially cleared paint substantially as indicated by the darts, while effecting eddy currents that successively tend to separate and trap the heavier materials therein.

10 The body of the paint as clarified by the successive action of the perforated diaphragm f and the frusto-conical members g, g', g'' , rises into the filter box h positioned at the top of the bowl. The separable casing h' thereof is provided with spacing rings h'' which engage the wire screen h , somewhat diagrammatically shown in Fig. 3 upon a larger scale, and this ordinarily has associated therewith a fibrous filter medium h'' , of silk or the like, 15 for the purpose of removing still finer solid ingredients from the paint. The filtered paint finds exit from the filter box through the openings h^3 , from which it is collected through the discharge spout j' . It will be observed that an upper spout j is provided merely for the overflow from the paint supply, either when it is excessive or after the bowl becomes charged with solid material 20 and requires to be cleaned out.

25 30 The bowl in turn is readily opened by unscrewing the clamping ring a^4 , whereupon the deflector members, the perforated diaphragm and vanes may be removed for the purpose of clearing from the bowl the accumulated pigment material. The separated solid ingredients very much resemble putty in consistency. After the clamping ring a^4 and cover a^3 have been removed from the bowl, one operation will serve to lift out the 35 center cones, together with the diaphragm and vanes in order to clear the bowl. These vanes subdivide the heavier sediment, so that it may readily be scraped out of the bottom of the bowl, while the removable parts are 40 cleaned for resuming separation.

45 My improved separable filter affords a novel and advantageous construction in that the fine screen, gauze or other filtering materials are held away from the box by spacing rings of wire, thus affording free passage for the paint to escape after filtration.

50 As previously stated, this type of separator readily lends itself as well to the separation of varnish materials and other fluids 55 charged with solids and partially dissolved

materials that do not lend themselves readily to ordinary separator treatment. Its construction lends itself to easily cleaning, not only the bowl, the deflector members, but the associated filter device, as well.

60

Having now shown and described the preferred embodiment of my invention, I claim as new and desire to secure by Letters Patent, together with such modifications thereof as may be made by those ordinarily skilled in the art, the following:

1. A centrifugal separator equipped with a central supply feed beneath a perforated diaphragm substantially closing the lower portion of the bowl, and a superposed axial 70 deflecting member.

2. A centrifugal separator equipped with a central supply feed beneath a perforated diaphragm and a superposed frusto-conical deflecting member adjacent to the perforations.

3. A centrifugal separator equipped with a central supply feed associated with a central deflecting member having abrupt lower faces and inclined upper faces.

4. A centrifugal separator equipped with a central supply feed, a perforated diaphragm, and a superposed series of upwardly inclined frusto-conical deflecting members positioned in the line of discharge of the perforated diaphragm.

5. A centrifugal separator equipped with a central supply feed to the bottom of the bowl, a perforated diaphragm substantially closing the lower portion of said bowl, and a central deflecting member having abrupt lower faces and gradually inclined upper faces.

6. A centrifugal separator equipped with a central supply feed, a centrally perforated diaphragm substantially closing the lower portion of the separator bowl, vanes thereon for impelling the fluid and deflecting means positioned adjacent to the axis of the bowl in the line of discharge from the perforations.

7. A centrifugal separator equipped with an axial supply feed beneath a centrally perforated diaphragm substantially closing the lower portion of the separator chamber, and an axially positioned deflecting member above said perforations provided with abrupt lower faces and tapering upper faces.

In testimony whereof I do now affix my signature.

JOHN IVAN FRITZ.
